Patented Feb. 21, 1922.

UNITED STATES PATENT OFFICE.

JOHN S. TIMMONS, OF NEW YORK, N. Y.

ELECTRIC SWITCH.

1,407,603.

Specification of Letters Patent. Patented Feb. 21, 1922.

Application filed July 16, 1919. Serial No. 311,177.

To all whom it may concern:

Be it known that I, JOHN S. TIMMONS, a citizen of the United States, and a resident of New York city, county and State of New York, have invented certain new and useful Improvements in Electric Switches, set forth in the following specification.

This invention relates to electric switches and more particularly to the type employed in the control of telephone circuits. The particular advantage of the invention is in its application to the control of telephone switches contained in a water-tight casing such as that described in my co-pending application for a casing for telephone sets, Serial No. 294,441, filed May 3, 1919.

An object of the invention is to provide for the ready manipulation of circuits by the movement of a part on the exterior of such a casing when the contact or switch devices themselves are protected within the casing. A further object of the invention is to provide an electric switch which may be completely assembled and disassembled with expedition and dispatch. A further object of the invention is to provide such a switch as can readily be carried by the hinged cover of the casing of a telephone set. A still further object of the invention is to provide an efficient water seal between the exterior manipulating parts and the interior contact devices. Likewise, it is an object to protect the projecting manipulating parts against mechanical injury and, at the same time, prevent injury to any of the essential movable parts of the switch, even when the mechanism is subjected to rough usage.

A still further object of the invention is to produce an extremely simple, cheap and readily inspected switch mechanism for the control of electric circuits and one which is adaptable, with minimum alteration, to various types of control with substantially standard mechanism.

A preferred and modified embodiment of my invention is shown in the drawings and described in the following specification, merely for the purpose of illustration, and the accompanying claims are to be considered as explained rather than limited thereby.

In the drawings, Fig. 1 is a fragmentary horizontal section taken along line X—X of Fig. 3, through the face plate or door of a casing for a telephone set, with parts of the switch mechanism shown in plan;

Fig. 2 is a vertical section through the face plate showing the switch mechanism in side elevation;

Fig. 3 is an interior elevation of the switch mechanism;

Fig. 4 is a view corresponding to Fig. 2 but drawn to a reduced scale and showing a modification;

Fig. 5 is a view corresponding to Fig. 1, showing the modification of Fig. 4;

Fig. 6 is a perspective view of one form of a switch-block; and

Fig. 7 is a perspective view of another form of switch-block.

The face plate or door 2 serves as a mounting for the switch mechanism and for each switch is preferably formed with an inwardly extending nipple 3 cast integrally with the face plate, the interior 4 of which is outwardly flared to facilitate drainage and assembling. This recess 4 is preferably superposed by a semi-circular roof-like flange *a* serving as a water-shed and protector for the finger-key or finger-lever 6, which is suitably formed as a mechanical part of the throw-shaft 5 as by being secured to the same, the pin 7 satisfactorily serving this purpose. This finger key 6 normally is designed to occupy a vertically dependent position and serves as a finger operable handle with a movement to left or right between the stops *b* and *c* formed on the face plate 2. The counter-sinking of the finger lever 6 within the nipple opening 4 and also its protection by the shed *a* makes it practically impossible for the mechanism to receive such a blow as might bend the throw-shaft 5. Any likely blow received by the same will tend to shift the lever or key from side to side, its yielding relieving the shaft 5 from injury.

The shaft 5 passes freely through the bearing opening *d* in the nipple 3 into the cavity on the inner side of the face plate 2, where the shaft is provided preferably with a flattened portion 5* or any other formations serving the purpose of a key-way.

Packing washers 8 and 9 of suitable material such as rubber, leather or brass, either both of the same kind of material or of different materials, are located preferably between the butt of the finger lever 6 and the bottom wall of the cavity 4 to serve as a water seal.

The inner end of the shaft 5 may likewise be fitted with similar washers 17 and 18 which, however, are preferably brass and

serve as spacers for one or more switch blocks 10, sliding freely over the inner end of the shaft 5. These blocks have an opening 10^a corresponding to the non-circular contour of the inner portion of the shaft 5 so that they are locked against rotation relatively to the shaft 5 and are rotatably operable by the said shaft. If two or more blocks 10 are to be employed on a single shaft 5, it is preferable that they be spaced by suitable means such as a washer 10^b of less diameter than the blocks.

In the embodiment of Figs. 1, 2 and 3 the rotatable mechanism is maintained assembled by a compression spring 19 surrounding the inner end of the shaft 5 and held in position by a washer 20 which is provided with a right angular inwardly extending flange 20^a, serving as an assembly washer to lock the assembly pin 21, which passes through the inner end of the shaft 5. This pin 21 or the pin and washer 21 and 20 may be considered a releasable stop between which and the face plate 2 the spring 19 reacts to force the butt of the finger lever 6 firmly against its seat in the bearing *d*. The reaction of the spring traverses one or more blocks 10 and the washers 17 and 18, so that all parts are held against rattling and so that any wear is automatically taken up.

Each switch block 10 has one or more radially extended switch operating parts such as the corners *e*' or *e*^a. In the embodiment shown the switch blocks are preferably moulded from suitable insulating material such as electrose or bakelite and the corners *e* bound intermediate flat faces, although it is to be understood that it is merely the radially extended parts which are functionally employed. The switch blocks may be provided with more or less circularly extensive cylindrical portions *f* coaxial with the axis of the shaft 5 which, unlike the parts *e* which extend radially beyond the surface of these cylindrical portions, are inactive in circuit manipulation.

It is preferred that one or more finger springs such as 11 and 12 normally press each against one or two of the radially extended parts *e* of a switch block, the positioning of the blocks and springs being such that the resilience tends to hold the finger lever 6 in its normal vertical position. In the drawings the finger springs 11 and 12 are shown as part of a set of a plurality of spring contact fingers 23 and 29 provided, as is customary, with contact devices 24 and 30 respectively. These sets of springs are suitably mounted and insulated through the medium of insulating blocks 26 and screws 28 upon a bracket 22, which is conveniently fixed to a boss 22^a, preferably formed integrally with the face plate 2, through the medium of screws 22^a. Connections with the various circuits from the fingers 23 and 29

are provided by the terminal eyes 23^a. It is to be understood that any reasonable number of spring fingers may be associated with a switch block in each set and that the number may be increased in sets by the addition of more switch blocks or by the axial extension of a single switch block.

When the switch block of Fig. 7 is employed as shown in Fig. 3, a clockwise rotation of the shaft 5 closes only the spring fingers 23, the cylindrical portion *f* having no effect upon the fingers 29. However, a counter-clockwise rotation of the shaft 5 closes both the spring fingers 23 and the spring fingers 29 through the pressure exerted by the radially extended portions *e*' and *e*^a, whereas *e*^a alone functioned with a clockwise movement.

If the switch block of Fig. 6 were employed, only one set of spring fingers at a time would be operated upon a throw of the finger key operating the throw-shaft 5.

Especially when the inward projection of the shaft 5 is considerable, it is preferred to modify the structure by providing a bracket 90 suitably mounted upon the face plate 2 and serving in addition as a support for the spring fingers to provide a stay bearing *g* on a lateral extension *h* for the inner end of the shaft 5, which passes through it. A perforation *i* is preferably provided in this arm to provide screw-driver access to the underlying screw 22^a. In this embodiment the compression spring 19 bears and reacts directly against the arm *h* and through the arm *h* against the face plate 2. With this modification the face plate bearing structure may be that of the embodiment of Figs. 1, 2 and 3 or, if desired, the butt of the finger lever 6 may have a conical bearing *j* working in a conical recess *k* in the nipple 3, which is efficient in providing itself a water-tight union, especially when close contact is maintained through the medium of the spring 19.

What is claimed and what is desired to be secured by United States Letters Patent is:

1. A switch comprising a protecting face-plate; a throw-shaft rotatably mounted in and passing through said face plate and having provisions to prevent the inward move-
ment of said shaft; one or more switch-blocks axially slidably on said shaft but fixed against rotation relatively thereto and having radially extended switch operating parts; a releasable stop on the end of said shaft; and a compression spring on said shaft reacting between one of said one or more blocks and said stop, whereby the assembled parts have an automatic take-up against wear.

2. A switch comprising a protecting face-plate; a throw-shaft rotatably mounted in and passing through said face plate and having provisions to prevent the inward move-

ment of said shaft and providing a water-tight seal against said face plate; one or more switch-blocks axially slidable on said shaft but fixed against rotation relatively thereto and having radially extended switch operating parts; a releasable stop on the end of said shaft; and a compression spring on said shaft reacting between one of said one or more blocks and said stop, whereby the 10 assembled parts have an automatic take-up against wear.

3. In an electric switch, a rotary throw-shaft having a stop-portion; a fixed bearing member for said shaft, itself alone permitting both axial and rotary movement of said shaft; one or more switch operating parts axially movable on said shaft but fixed against rotation thereon; and a take-up spring releasably attached against axial 20 movement to said shaft and reacting against said bearing member to draw said stop portion against said bearing member and to maintain all parts operatively assembled while facilitating disassembling.

25 4. An electric switch comprising a face plate providing a transverse bearing; a

throw-shaft having an external finger-key and mounted to rotate in said bearing; one or more switch-blocks non-rotatably fixed to said shaft inside of said face plate and each 30 having radially extended switch operating parts; and one or more spring switch-fingers normally pressing against one or more of said switch operating parts to hold said finger-key in normal position and operable by 35 a manipulation of said key to operate one or more of said spring switch fingers.

5. A switch comprising a protecting face plate; a throw-shaft rotatably mounted in passing through said face plate and having 40 provisions to prevent the inward movement of said shaft; one or more switch blocks axially slidable against said shaft but fixed against rotation relatively thereto and provided with finger operating means; and resilient means reacting between the end of said shaft and the nearest switch block to maintain the assemblage of the parts.

In witness whereof I have signed my name to this specification, this 29th day of 50 May, 1919.

JOHN S. TIMMONS.
